UNITED STATES PATENT OFFICE.

LOUIS SMITH, OF CHICAGO, ILLINOIS.

COMBINATION-TOOL.

SPECIFICATION forming part of Letters Patent No. 726,365, dated April 28, 1903.

Application filed May 12, 1902. Serial No. 107,000. (No model.)

To all whom it may concern:

Be it known that I, LOUIS SMITH, a citizen of the United States, and a resident of the city of Chicago, county of Cook, and State of Illinois, have invented certain new and useful Improvements in Combination-Tools; and I do hereby declare that the following is a full, clear, and exact description thereof, reference being had to the accompanying drawings, and to the letters of reference marked thereon, which form a part of this specification.

This invention relates to a combination-tool, and more particularly to combined gripping and cutting pliers.

The object of the invention is to provide cheap and simple gripping-pliers of great strength adapted to be readily converted into a cutting-tool when so desired.

The invention consists in the matters hereinafter described, and more fully set forth and defined in the appended claims.

In the drawings, Figure 1 is a side elevation of a pair of gripping-pliers provided with adjustable cutting-blades and showing the same retracted. Fig. 2 is a similar view showing the cutting-blades in cutting position. Fig. 3 is an end elevation taken at the hinge or joint. Fig. 4 is a cross-sectional view through the gripping-jaws and cutters, the holding-pins for said cutters being shown in elevation. Fig. 5 is a side elevation showing the removable jaws.

As shown in said drawings, A and A' indicate the two arms or levers of the gripping-pliers, which are united at the extremities in the hinge (indicated as a whole by B) and shaped adjacent thereto to form seats for the gripping-jaws a a'. Said hinge is constructed, preferably, as follows: One of said arms or levers—as, for instance, A'—is cut away centrally, as shown in Fig. 3, to provide the rounded lateral knuckles b' b', between which the knuckle b on lever A engages. A rivet or pintle (indicated by B') is passed through the joint thus formed, and the ends thereof are closed down and firmly engaged on the knuckles b' b'. The inner ends of said levers or the jaws adjacent to the hinge are suitably shaped on their adjacent sides to enable the same to grip material of desired forms and

sizes. Preferably a link C is provided on the outer extremity of one of said levers and engages over the other arm and acts to hold the jaws in gripping position when once secured. Pivoted at e on each of said levers adjacent to the hinged end thereof are cutters D, which are of a length to extend rearwardly a sufficient distance to engage material gripped between the jaws. Said cutters or knives are normally held in a retracted or inoperative position by means of the pins or set-screws d, which extend therethrough and engage suitable apertures d' in the levers, said pins or screws being adapted to be removed to permit the knives to be swung inwardly upon their pivots e to cause their cutting edges to approach, as in Figs. 2 and 4, when the pins or screws d may be inserted in the innermost apertures d' to lock the knives in cutting position.

Obviously many different types of instruments may be constructed substantially as described with the cutters pivoted as preferred to operate either adjacent to the hinge or remote therefrom.

The seat in the inner faces of the lever may be of any desired form, and the removable jaws a a' are shaped to fit closely therein and to be secured in place by set-screws, as shown in Fig. 5. Said jaws may be provided in sets having differently-shaped gripping-surfaces, thus enabling one pair of pliers to be used for as many different purposes as desired.

Details of construction may be varied without departing from the principles of this invention.

I claim as my invention—

1. A combination-tool comprising coacting levers complementally shaped at one end to interfit and form a hinge, said levers adjacent to the hinge thus formed being shaped to provide gripping-surfaces, and adjustable cutters pivoted on the levers and adapted to be adjusted into cutting engagement with the material engaged between said levers.

2. In a combination-tool, the combination with levers shaped to interfit and form a hinge at one end of a knife pivoted on each end adjacent to the hinge, a set-screw engaging in each lever and acting normally to hold the

knives out of cutting relation and removable to permit adjustment of the knives.

3. The combination with levers hinged at their ends, of recesses in the inner side of each adjacent to the hinge, removable gripping-jaws seated in said recesses, and coacting cutting-blades carried on each lever.

In testimony whereof I have hereunto subscribed my name in the presence of two subscribing witnesses.

LOUIS SMITH.
